UNITED STATES PATENT OFFICE

149,499

DESIGN FOR A BEVERAGE STIRRER

Elaine E. Holden, Lancaster, Pa.

Application September 13, 1946, Serial No. 133,304

Term of patent 14 years

(Cl. D44—29)

To all whom it may concern:

Be it known that I, Elaine E. Holden, a citizen of the United States of America, residing at Lancaster, in the county of Lancaster and State of Pennsylvania, have invented a new, original, and ornamental Design for a Beverage Stirrer, of which the following is a specification, reference being had to the accompanying drawing, forming a part thereof, wherein:

Figure 1 is a perspective view of a beverage stirrer, showing my design.

Figure 2 is a view in elevation.

Figure 3 is a top plan.

Figure 4 is a bottom plan.

I claim:

The ornamental design for a beverage stirrer, as shown.

ELAINE E. HOLDEN.
